Int. Cl. D9—01

U.S. Cl. D9—156

FIG. 1

FIG. 2

FIG. 3

FIG. 4

FIG. 1 is a front elevational view of a combined cruet and stopper showing my new design;

FIG. 2 is a top plan view thereof;

FIG. 3 is a side elevational view thereof; and

FIG. 4 is a sectional view taken on line 4—4 of FIG. 3.

The back is the same in appearance as the front which is shown in FIG. 1, and the side opposite that seen in FIG. 3 is the same in appearance as the side shown.

This application is a continuation-in-part of my co-pending application Ser. No. D. 458,132, filed on Apr. 5, 1974.

I claim:

The ornamental design for a combined cruet and stopper, substantially as shown and described.
